[57] CLAIM

The ornamental design for a combined electronic flash unit and adapter module, substantially as shown and described.

DESCRIPTION

FIG. 1 is a front elevational view of a combined electronic flash unit and adapter module showing my new design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a bottom plan view thereof with the adapter module portion omitted for ease of illustration;

FIG. 8 is a top plan view of the adapter module portion with the flash unit portion omitted for ease of illustration;

FIG. 9 is a front elevational view of another embodiment of my new design of FIGS. 1-8;

FIG. 10 is a right side elevational view thereof;

FIG. 11 is a rear elevational view thereof;

FIG. 12 is a left side elevational view thereof;

FIG. 13 is a top plan view thereof;

FIG. 14 is a bottom plan view thereof;

FIG. 15 is a bottom plan view thereof with the adapter module portion omitted for ease of illustration;

FIG. 16 is a top plan view of the adapter module portion with the flash unit portion omitted for ease of illustration.
